COMBINED DRY SHAVER AND HAIR CLIPPER

Henricus Franciscus Theresia Schellens, Drachten, Netherlands, assignor to North American Philips Co., Inc.

Filed Apr. 18, 1966, Ser. No. 1,918

Claims priority, application Switzerland Nov. 24, 1965

Term of patent 14 years

(Cl. D95—3)

FIG. 1 is a perspective view of a combined dry shaver and hair clipper, showing my new design;

FIG. 2 is a right side elevational view thereof;

FIG. 3 is a left side elevational view thereof;

FIG. 4 is a top view thereof;

FIG. 5 is a bottom view thereof;

FIG. 6 is a rear elevational view thereof;

FIG. 7 is a front elevational view thereof;

I claim:

The ornamental design for a combined dry shaver and hair clipper, as shown.
